INK PAD FOR DUPLICATING MACHINES

Robert A. Dalton, Bridgeport, Conn., assignor to
Remington Rand Inc., Buffalo, N. Y., a corporation of Delaware

Application September 8, 1938, Serial No. 228,985

5 Claims. (Cl. 101—415.1)

My invention relates to stencil duplicating machines, and more particularly to improvements in an ink pad for use on such machines.

One of the main objects of my invention, generally stated, is to provide an improved, highly efficient and reliable ink pad for use on stencil duplicating machines.

A more specific object of my invention is to provide in an ink pad comprising a textile fabric sheet and a metal attaching member, an improved means for securing the fabric sheet to the metal attaching member.

To the above and other ends which will hereinafter appear, my invention consists in the features of construction, and arrangements of parts set forth in the following description and particularly pointed out in the appended claims.

In the drawings, wherein like reference characters designate corresponding parts in the different views:

Fig. 1 is an enlarged fragmentary plan view of an ink pad constructed in accordance with the present invention.

Fig. 2 is an enlarged fragmentary sectional view of the same taken on line 2—2 of Fig. 1 and viewed in the direction of the arrows at said line.

Fig. 3 is an enlarged fragmentary sectional view of a portion of the same taken on line 3—3 of Fig. 2 and viewed in the direction of the arrows at said line.

Fig. 4 is an enlarged fragmentary perspective detail view of a textile fabric sheet of the ink pad without the metal attaching members secured thereto.

Fig. 5 is a detail perspective view of one of the metal attaching members shown as it appears before it is connected to the cloth of the pad.

Fig. 6 is a sectional view of the same taken on line 6—6 of Fig. 5 and viewed in the direction of the arrows at said line.

In certain well known types of duplicating machines, a rotary cylinder is employed which is provided with a perforated outer diaphragm, over which is placed and stretched a textile fabric ink pad and a stencil sheet is secured around the outer surface of the pad. The ink pad of such machines is of a textile fabric material or cloth which must be renewed from time to time, and accordingly it is desirable to provide an ink pad constructed and arranged so that it can be smoothly and securely attached to the diaphragm of the machine and yet which may be readily removed for replacement or for reversal of the position thereof on the diaphragm.

As shown in Fig. 1 of the drawings, the present ink pad comprises a sheet 10 of suitable textile material having an attaching member 12 secured to each end thereof. The present inven-

tion is concerned primarily with an improved means for securing these attaching members 12 to the ends of the sheet 10.

Heretofore difficulty has been found in effectively connecting the ends of the cloth 10 to the metal attaching members without employing comparatively expensive methods for effecting the desired result. It is one of the objects of the present invention to overcome these difficulties and to provide simple and effective means to attain the result, the connection being readily effected in an inexpensive manner.

The construction and arrangement of the textile sheet 10 before the attaching members 12 are secured thereto is shown in Fig. 4 wherein it may be seen that a hem is formed at each end of the sheet 10 by portions 10' of the sheet which are folded over and stitched at 11 to form a loop of the cloth or fabric at each end of the sheet 10. In some instances it may be found desirable to turn in the raw edge of the fabric in forming these hems in the usual manner to prevent fraying or raveling thereof.

Each of the attaching members 12 in the present instance is of thin sheet metal and before being attached to the fabric 10 is preferably of a shape shown in Fig. 5. These attaching members 12 are adapted for convenient attachment to the cylinder or diaphragm of the duplicating machine. In the form of the attaching members shown in the drawings, there are circular perforations 13 provided therein which receive pins or projections ordinarily provided for attaching the ink pad to the cylinder or diaphragm of the duplicating machine. It will be clear that these perforations 13 will be adapted by size and spacing to the ink pad securing means provided on the machine in which the present ink pad is to be used. Each of the attaching members 12 may be reinforced by bending over a portion 12' along one of the edges thereof.

An open loop or channel 12² is formed continuously along the other edge of each of the attaching members 12 before the sheet 10 is attached thereto. This open loop or channel of each of the attaching members is adapted to receive a portion of the hem at one end of the sheet. In order to evenly and securely hold the end portions of the sheet 10 to the attaching members 12, a filler which in the present instance is in the form of a cord 14 is placed in the loop formed by hem 10' at each end of the sheet. The cord or filler 14 is held taut against the outer end wall of the companion loop or hem of the sheet 10. That portion of each hem which contains the cord 14 is then seated in the open channel 12² of the companion attaching member 12 and one side wall of the channel is then crimped over the outer edge portion of the

hem to infold the portion of the hem which surrounds the cord 14, thereby clamping the cord and surrounding portion of the companion hem within the channel 12².

5 The side wall of the open channel 12² of each of the attaching members 12 may be crimped over the associated end of the sheet 10 by a suitable pressing device having a die adapted to close the edge portion of the attaching member forming the channel 12² inwardly against the fabric forming the loop in the sheet 10 as shown in Fig. 2. During this closing or crimping operation of the edge portion of the attaching members around the ends of the sheet 10, care should be 10 taken to hold the filler cord 14 taut and against the outer end wall portion of the companion loop or hem in the sheet 10. For this purpose, suitable means may be provided for gripping the extending ends of the cord 14 and for holding the 15 cord in a taut condition while the closing dies are crimping the edge portion of the attaching member over the companion hem.

In order to further secure the ends of the sheet 10 to the attaching member 12, a plurality of 20 indentations 16 are pressed into the portion of the attaching member which infold the hem of the sheet 10. These indentations 16 may be formed simultaneously with the closing operation of the side wall of the attaching member over 25 the hem of the sheet 10 by providing pointed punches on the closing die adapted to form small points 16^a on the folded over portion 12² of the channel which points pinch or are embedded in the fabric forming the hem at these points.

30 It will be noted in Fig. 2 that the attaching members 12 are applied in a reverse order to the opposite ends of the sheet 10. That is, the edge portion of one of the attaching members is crimped over one surface of the sheet 10 at one 35 end, while the corresponding edge portion of the other attaching member is crimped over the opposite surface of the other end of the sheet. It will also be observed in Fig. 2 that the hem portion at each end of the sheet 10 is doubled 40 backward over the edge of the companion attaching member, thereby covering this edge of the metal and providing an additional grip between the fabric and this metal edge. It will further be observed that the free edge of the 45 folded portion of each of the attaching members is crimped or closed against a double thickness of the fabric between the stitching 11 and the end of the companion hem thereby reducing the strain 50 on the threads of the fabric at these points.

55 It will be seen that I have thus provided a simple and highly effective means for securing the metal attaching members to the ends of a fabric ink pad. A particular feature of the present invention resides in the use of a filler disposed within a loop or hem at the ends of the fabric sheet to form a pre-formed bead, enlargement, ridge, or in effect, a shoulder, which is tightly interlocked in a single fold or a substantially closed loop formed in the associated metal attaching member. This shoulder or bead formed by the provision of a filler within the hem of the fabric when thus interlocked with the folded portion of an attaching member forms a continuous, uniform connection therewith throughout the entire width of the fabric sheet. Displacement of the fabric sheet from the metal attaching members is further prevented by the provision of projections 16^a on the metal which are forced into and pierce the hem portion of the fabric at spaced 65 intervals throughout its width.

Although I have shown and described the filler 14 disposed within the hem of the fabric as being a textile cord in the present instance, it will be clear that from certain aspects of my invention, a filler serving the same purpose could 5 be provided by using other materials. For example, it may in some instances be desirable to substitute a small metal rod or wire in place of this cord, or any other article or construction may be used which will form a ridge or bead at 10 the ends of the textile sheet 10 to be received in and interlock with the closed channel of the metal attaching members.

Various changes may be made in the construction, and certain features thereof may be omitted 15 without departing from my invention as it is defined in the accompanying claims.

What I claim as new and desire to secure by Letters Patent is:

1. In an ink pad for duplicating machines, the 20 combination of a fabric sheet having a loop at one end thereof formed by a free end portion of the sheet being stitched to the body portion thereof, a cord disposed within said loop, and a metal attaching member having a portion thereof 25 folded around the part of said loop which carries the cord to cause the edge of the attaching member to engage the loop between the stitching and the cord.

2. In an ink pad for duplicating machines, 30 the combination of a fabric sheet having a loop at one end thereof formed by a free end portion of the sheet being stitched to the body portion thereof, a cord disposed within said loop, and a metal attaching member having a portion folded 35 around the end of said loop to press the edge of the attaching member against the loop between the stitched portion and the portion carrying the cord and to cause the loop to extend around said edge of the attaching member.

3. In an ink pad for duplicating machines, the combination of a fabric sheet having a hem at each end thereof formed by fixedly securing a free end portion of the sheet to the body portion 40 thereof, a filler member disposed within each of 45 said hems adjacent the end wall thereof, and a metal attaching member for each end of said sheet, each of said attaching members being folded around the end of the companion hem to clamp the intermediate portion thereof between 50 the edge and body portion of the attaching member.

4. In an ink pad for duplicating machines, the combination of a fabric sheet having a hem at each end thereof formed by fixedly securing each 55 free end portion of the sheet to the body portion thereof, a filler member disposed within each of 60 said hems adjacent the end wall thereof, and metal attaching members for said sheet, said members being folded in relatively opposite directions around the ends of the respective hems to clamp the intermediate portions thereof and to cause the intermediate portions of the hems to extend around the edges of the respective attaching members.

5. In an ink pad for duplicating machines, the combination of a fabric sheet having a loop at one end thereof, a filler member disposed within 65 said loop adjacent the end wall thereof, and a metal attaching member extending beyond the 70 end of said loop and having a portion folded back over the part of the loop carrying the filler member, said loop being doubled over the edge of the folded portion of the attaching member.
